CLOSURE

Roy G. Miller, Bayside, N. Y., assignor to East Coast Aeronautics, Inc., New York, N. Y., a corporation of New York

Application June 18, 1947, Serial No. 755,441

5 Claims. (Cl. 220—40)

1

My invention relates to a two part closure consisting of cooperating neck and cap portions, said closure being especially designed and adapted for use in situations where it is desirable to maintain a smooth surface contour such as airplanes. My closure, as will be apparent from the disclosure to follow, may be used to close any opening with which the neck portion of the closure may be associated, for instance the filling openings of fuel tanks, inspection openings, etc.

An object of my invention is to provide a closure the neck portion of which may lie beneath the surface surrounding the opening to be closed and the cap portion of which may be smooth and flat or curved to conform to the contour of the surrounding surface. In this connection I wish to note that the smooth flat or curved surface of the cap is not essential but merely an optional generally advantageous feature. The cap surface may be of any desired shape. Moreover, the surface of the cap need not lie flush with the surface surrounding the opening which it closes, this also being merely an optional feature.

Another object of my invention is to provide a closure the cap portion of which may be inserted and removed without the use of any tool and without the provision of any handle or the like. This also is only an optional and generally desirable feature because as stated above the cap surface may be made of any desired shape, provided with a handle or ornament, etc. within the scope of my invention.

A further object of my invention is to provide a closure which is relatively simple and inexpensive and which is of relatively light weight.

A further object of my invention is to provide a closure which securely seals the opening and is not likely to fail as a result of careless manipulation, vibration or pressure within the container which it closes.

A further object of my invention is to provide a closure which permits complete filling of the container which it closes and does not require a scupper or scupper drain or an extensive cavity in which water may collect and freeze.

Still a further object of my invention is to provide a closure which is relatively free of wear particularly at the points or areas where the cap and neck engage each other in applying and removing the cap.

A further object of my invention is to provide a closure in which the cap is held firmly in closed position by strong parts of the structure and in which the sealing action of the cap is increased rather than decreased by pressure within a container.

2

A further object of my invention is to provide a closure in which packing is not subjected to rubbing friction in the insertion and removal of the cap and therefore does not interfere with the insertion and removal of the cap and is not worn by these operations.

Other objects and advantages of the invention will be pointed out in the following detailed description of an illustrative embodiment of the invention shown in the accompanying drawings in which:

Fig. 1 is a top plan view of the neck portion of the closure.

Fig. 2 is a central section of the neck portion of the closure on the line 2—2 of Fig. 1.

Fig. 3 is a section of the neck portion of the closure on the line 3—3 of Fig. 1 and

Fig. 4 is a central section of the closure showing the cap portion seated in the neck portion.

Referring to the drawings, 1 is a flange shown integral with the neck portion of the closure. The flange is provided for securing the closure to the wall or surface of the structure surrounding the opening to be closed such as for example the wall of a liquid fuel tank or an airplane wing or body surface. It will be appreciated that this flange may be omitted and substituted by other means for securing the closure neck to the material surrounding the opening. For example, the external surface of the neck might be provided with screw threads to engage screw threads in the edge of the material surrounding the opening or the outer surface of the neck might be soldered or welded to the edge or wall of material or structure surrounding the opening.

The neck of the closure consists of the cylindrical wall 2 provided adjacent its upper edge with the internal rounded sealing head 3. Adjacent its lower edge the neck is provided with the inwardly extending flange 4 which provides a seat for the spider member of the cap portion of the closure. Extending downwardly from the flange 4 is a cylindrical skirt 5 the lower edge of which is cut or shaped to provide a plurality of cam surfaces 6 (three illustrated) evenly distributed around the circumference of the skirt. The flange 4 and skirt 5 are completely cut away at three points to provide slots 7 for the passage of the dog members of the cap.

The cap portion of the closure comprises the disc 8, the top or outer surface of which may be of any desired shape but preferably is flat or curved to conform to the contour of the surrounding surface. Extending downwardly from the disc 8 is the cylindrical wall or skirt 9 provided with the external groove 10 which con-

3

tains the packing ring 11. The packing ring 11 may be circular in cross-section and formed of rubber or other suitable deformable packing material and preferably, as illustrated, is of less diameter than the vertical dimension of the groove 10 so that it may roll slightly in the groove. This facilitates the insertion of cap in the neck in that it permits the packing to roll instead of slide over the bead 3. The packing must of course have a greater diameter than the depth of the groove 10 so as to engage the bead 3.

Extending downwardly from wall 9 are the three fingers 12 at the lower ends of which are the outwardly extending dogs 13 which pass through the slots 7 and engage the cams 6.

The disc 8 also has at its center the downwardly extending cylindrical shaft or stud 14 which carries the spider 15 pressed downwardly by the spring 16 and retained by the pin 17. A washer 18 is inserted between the spring 16 and the spider 15 to facilitate relative rotation. The spider 15 is a circular disc of a size to rest on the flange 4 with portions cut away as indicated at 19 to permit relative rotary movement of the fingers 12. If desired, means (not shown) such as a cam on the lower surface of the spider 15 may be provided to straddle the retaining pin 17 and retain the spider 15 in the desired alinement with the fingers 12 so that after the cap is inserted in the neck the cap may be rotated to engage the dogs 13 with the cams 6 without rotation of the spider, i. e. so that the fingers 12 and dogs 13 move within the cut away portions 19 of the spider. This is not essential because the spider 15 may be rotated with the cap but its contact with the flange 4 and the pressure of the spring 16 causes it to offer considerable frictional resistance to rotational movement. It is noted that the legs of the spider are of sufficient width that they will not fall into or pass through the slots 7.

Means (not shown) such as a chain, cable or coil spring may be provided with one end attached to the stud 14 and the other end attached to the skirt 5 for preventing complete detachment and loss of the cap portion of the closure.

In operation the spider preferably is positioned on the cap with the counter-clockwise edges of the cut away portions in contact or substantially in contact with the fingers 12. The cap is then inserted in the neck. Since the dogs 13 extend slightly below the spider 15 it is easy to feel for the slots 7 by means of the dogs. As the cap enters the neck the spider 15 engages the flange 4 before the packing ring 11 engages the bead 3. The cap is then pushed downwardly compressing the spring 16. This downward movement brings the dogs 13 below the level of the cams 6 and also forces the packing ring 11 past the bead 3. The cap is then rotated to bring the dogs 13 under the cams 6 and released whereupon the pressure of the spring 16 downwardly against the spider 15 resting on the flange 4 and upwardly against the disc 8 raises the cap until the dogs 13 engage the cams 6. The dimensions of the parts are such that when the dogs 13 are seated on the cam surfaces the disc 8 lies flush with the upper edge of the neck and the packing ring 11 is pressed upwardly against the bead 3 as shown in Fig. 4.

To remove the cap the disc 8 is pressed downwardly and rotated counter-clockwise to bring the dogs 13 to the slots 7 whereupon the pressure on the disc 8 is released and the cap is forced upwardly by the spring 16 to a position

4

where it can be grasped by the fingers and removed from the neck.

As will be apparent neither the rotation of the cap clockwise in inserting it nor the rotation counter-clockwise in removing it involves any considerable amount of friction because in these operations the only frictional contact is between the spring 16 and the washer 18, the dogs 13 being clear of the cam surfaces 6 and the packing ring 11 being clear of the bead 3 and there being no relative movement between the spider 15 and the flange 4. Consequently, the cap may be inserted and removed by simply pressing the hand against the flat smooth surface of the cap and no handle or tool is required.

The inclined cam surfaces and the spring tension prevent accidental rotary movement of the cap to its released position and tend to hold the cap in its fully engaged position. If, when the cap is inserted, it is not rotated to fully engaged position it will tend to seek this position rather than to seek the released position.

It will be noted that there is very little space between the packing ring and the surface of the cap for the accumulation of water, ice or snow. The small amount of ice that may form in this space readily may be broken to remove the cap.

It will be appreciated that the specific neck and cap structures described above are capable of extensive modification within the scope of my invention which resides in any cap and neck combination which includes (1) cooperating means on the neck and cap for releasably securing the cap in a fixed position with respect to the neck, i. e. cooperating means equivalent to the dogs 13 which occupy a fixed position with respect to the cap and the cam surfaces 6 which occupy a fixed position with respect to the neck; (2) cooperating bead and packing which permit the cap to be inserted in the neck beyond its normal closed position and engage each other in sealing contact as the cap rises in the neck to its normal closed position, i. e. cooperating means equivalent to the bead 3 and the packing ring 11; and (3) cooperating fixed and movable resilient means permitting the insertion of the cap in the neck beyond its normal closed position but resiliently urging the cap outwardly to its closed position, i. e. cooperating means equivalent to the flange 4 and the spider 15 and spring 16.

I claim:

1. A two part closure comprising a neck portion and a cap portion, said neck portion comprising a first cylindrical wall, a bead extending inwardly from said first cylindrical wall, spaced apart arcuate sections of an inwardly projecting flange adjacent one end of said first cylindrical wall, spaced apart arcuate sections of a second cylindrical wall of less internal diameter than said first cylindrical wall extending from said flange sections, and cam surfaces on the free edges of said arcuate sections of said second cylindrical wall, and said cap portion comprising a circular disc, a third cylindrical wall extending from one face of said disc, a groove in the outer surface of said third cylindrical wall; a packing ring in said groove, fingers extending from said third cylindrical wall perpendicularly to said disc, outwardly projecting dogs at the free ends of said fingers and a spider flexibly supported parallel to but spaced apart from said face of said disc, said spider, packing ring and dogs respectively of said cap portion being adapted to engage said flange, bead and cam surfaces respectively of said neck portion.

2. A two part closure as defined in claim 1 in which the spider is supported on a stud extending downwardly from the center of the disc, said spider being slideable lengthwise of said stud and rotatable thereon and resilient means for pushing said spider away from said disc.

3. In a two part closure a cap member comprising a disc, a cylindrical wall of less external diameter than the disc depending therefrom, a flange extending outwardly from said wall and spaced apart from said disc, a packing ring supported in the groove between said flange and the edge of said disc on the outer surface of said wall, fingers depending from said wall, outwardly extending dogs adjacent the ends of said fingers, a stud extending perpendicularly from the center of said disc, a spider slidably and rotatably supported on said stud and resilient means urging said spider away from said disc.

4. A two part closure comprising a neck portion and a cap portion, one of said portions comprising a bead and the other comprising a packing of such relative sizes as to engage each other when the cap portion is in its normally closed position in the neck portion but to allow one to pass the other when the cap portion is inserted into the neck portion beyond its normally closed position, cooperating means on said portions for releasably securing the cap portion in normally closed position in said neck portion, said means permitting the insertion of the cap portion into the neck portion beyond its normally closed position and means resiliently urging said cap portion from said position beyond its normally closed position toward its normally closed position.

5. A two part closure comprising a neck por-

tion and a cap portion, said neck portion having a first cylindrical wall and a bead extending inwardly from the inner surface thereof, said cap portion comprising a second cylindrical wall and a packing ring supported on the outer surface thereof, said packing ring being of such a size and compressibility that it clears said first cylindrical wall but engages and makes sealing contact with and springs past said bead when the cap portion is inserted into and engaged with said neck portion and cooperating means on said cap and neck portions for securing the same in closed position, said means comprising resilient means urging the cap outwardly to maintain sealing contact between said ring and said bead.
